(57) **CLAIM**

I claim the ornamental design for a garden clog shoe, as shown and described.

DESCRIPTION

FIG. 1 is a Perspective view of a garden clog shoe showing my new design;

FIG. 2 is Front view thereof;

FIG. 3 is a Back view thereof;

FIG. 4 is a Right-side view thereof;

FIG. 5 is a Left-side view thereof;

FIG. 6 is a Top-side view thereof;

FIG. 7 is a Bottom view thereof; and,

FIG. 8 is perspective view of a garden clog shoe thereof in bend position.

In the drawings, the broken lines depict portions of the garden clog shoe that form no part of the claimed design.
